UNITED STATES PATENT OFFICE.

THEODORE W. FOSTER, OF PROVIDENCE, RHODE ISLAND.

DESIGN FOR AN EAR-RING.

SPECIFICATION forming part of Design No. 15,599, dated December 9, 1884.

Application filed September 19, 1884. Term of patent 7 years.

To all whom it may concern:

Be it known that I, THEODORE W. FOSTER, of Providence, in the State of Rhode Island, have invented and produced a new and original Design for Ear-Rings, of which the following is a specification, reference being had to the accompanying drawings, forming a part thereof.

Figure 1 is a front view of my newly-designed pendent jewelry ornament employed as an ear-ring. Fig. 2 is a side elevation of the same. Fig. 3 is a central longitudinal section of the ornament. Fig. 4 is a transverse section of the same, taken in the line $x-x$ of Fig. 1.

The leading feature of my design consists in a pendent jewelry ornament the outline and front surface of which represents a dust-pan

and its handle, the surface of the pan being provided with ornamentation.

In the accompanying drawings, A is the ornamental plate of an ear-ring in the form of a dust-pan, consisting of the pan *a* and the handle *b*, provided with the ring *c*, the face of the pan *a* being provided with ornamentation.

I claim—

The design for an ear-ring herein shown and described, the same consisting of a plate the outline and front surface of which represents a dust-pan and its handle, the face of the pan being provided with ornamentation.

THEODORE W. FOSTER,

Witnesses:

SOCRATES SCHOLFIELD,
CHAS. F. SCHMELZ.
